Primary Examiner — Mark Goodwin(74) *Attorney, Agent, or Firm* — Wegman, Hessler & Vanderburg(57) **CLAIM**

We claim the ornamental design for a robotic mower housing, as shown and described.

DESCRIPTION

FIG. 1 is a top perspective view of a robotic mower housing showing my new design;

FIG. 2 is a bottom perspective view thereof;

FIG. 3 is a right side view thereof;

FIG. 4 is a left side view thereof;

FIG. 5 is a rear view thereof;

FIG. 6 is a front view thereof;

FIG. 7 is a top view; and,

FIG. 8 is a bottom view.

The ornamental design which is claimed is shown in solid lines in the drawings. Any broken lines in the drawings are for illustrative purposes only and form no part of the claimed design.

1 Claim, 8 Drawing Sheets(56)
